8 Claims. (Cl. 200—61.45)

This invention relates to electric switches and more particularly to switches operable to close an electric circuit when a device to which the switch is attached is subjected to an accelerating or decelerating force.

Accordingly there is provided a switch operable to close an electrical circuit when an accelerating or decelerating force is applied to a device to which the switch is attached, comprising a body, a slug movable within a cavity in said body and means for initially retaining said slug in the bottom of the cavity so that application of said force causes the slug to move towards that portion of the body forming the top of the cavity to close said circuit.

I prefer to shape the side wall of the cavity and the slug so that the latter hinges about the side wall on application of said force.

So that the switch may be used in rotating devices subjecting the switch to centrifugal forces, the slug is disc-shaped and the means for initially retaining the slug in the bottom of the cavity exerts a force which retains the slug on the bottom of the cavity whilst allowing it to slide thereover to contact the side wall when the switch is subjected to centrifugal forces.

In order that the invention may be fully understood, preferred embodiments thereof will now be described with reference to the accompanying drawings in which:

FIGURE 1 shows a sectional view of a preferred embodiment of the present invention, and

FIGURE 2 shows a sectional view of a modification of the switch shown in FIGURE 1.

In FIGURE 1 a switch 1 has a body 2 comprising an electrically conductive annulus 3 having a cylindrical inside wall 4 held between an insulating ring 5 and an electrically conductive top plate 6 and a laminated plate 7 comprising a spacer 8, a magnet 9 and a backing plate 10. The spacer 8, annulus 3 and top plate 6, together form a closed cavity 11 within the body 2 which contains a disc shaped electrically conductive slug 12. The slug 12 is initially retained on the bottom of the cavity 11 formed by the spacer 8 by the magnetic force exerted by the magnet 9. The diameter of the slug 12 is less than that of the inside diameter of the annulus 3. Secured to the plate 6 is an electrical contact wire 13, another contact wire 14 being passed through and insulated from the plate 6 to make contact with the annulus 3. The ring 5 is also annular, its central aperture 15 being co-axial with the cylindrical inside wall 4 of the annulus 3. The upper and lower edges 16 and 17 respectively of the slug 12 are bevelled to provide an edge 18 which contacts the cylindrical inside wall 4 of the annulus 3 to provide a hinge point for the slug 12 as will be described in detail hereinafter.

The switch has been designed with such applications in mind as impact switches for artillery shells where high decelerating forces are encountered but it will be appreciated that such a switch may also be used in applications where it is desired to close an electrical circuit when the device to which it is attached is subjected to accelerating or decelerating forces.

To take the example of an artillery shell which is subjected to spin by the rifling of the gun barrel from which it is fired, the slug 12 will first be thrown against the side wall 4 of the annulus 3 by the centrifugal force acting on the switch which is mounted at right angles to

2

the axis of the shell. The decelerating force experienced by the switch when the shell hits an object overcomes the force of the magnet 9 holding the slug 12 on the bottom of the cavity 11, to hinge the slug 12 about the edge 18 in contact with the side wall 4 of the annulus 3 to take up a position in which the left hand side of the slug 12 is in contact with the top plate 6 completing an electrical circuit through wire 13, top plate 6, the slug 12, annulus 3 and wire 14.

10 The force exerted by the magnet 9 on the slug 12 may be varied by altering the thickness of the spacer 8 so that the switch may be adjusted to operate in conditions in which only small decelerating forces are experienced.

FIGURE 2 shows a switch 30 having parts which are 15 the same as those shown in FIGURE 1, and in consequence bear the same reference numerals. In FIGURE 1, the slug 12 is retained in the bottom of the cavity 11 by means of the magnet 9 but in FIGURE 2, a slug 31 is retained in the bottom of the cavity 11 by means of 20 a spring 32 clamped between the insulating ring 5 and annulus 3 from which the spring is electrically insulated. The spring may be a disc or a strip. The slug 31 is similar to slug 12 shown in FIGURE 1 but the top portion 33 of slug 31 is domed.

25 The operation of the switch 30 is the same as that of the switch 1 shown in FIGURE 1 described earlier in this specification with the exception that the decelerating force experienced by the switch when the shell in which the switch is mounted hits an object, causes the slug 31 to hinge about the edge 18, the domed portion 33 deforming the spring 32 to contact the top plate 6 and thus close the electrical circuit connected to wires 13 and 14. To vary the value of the minimum decelerating force at 30 which the switch will operate to close an electrical circuit, different springs may be used to provide different restraining forces on the slug 31.

Whilst the top plate 6 and annulus 3 are, in the preferred embodiments shown in FIGURES 1 and 2, made of electrically conductive material they may also be made 40 of insulating material with metallic contacts or a layer of conductive material secured to the face of the top plate 6 forming the top of the cavity 11 and the inside wall 4 of the annulus 3.

The switch as shown in FIGURES 1 and 2 may be 45 encapsulated to precise dimensions in an epoxy injection mould tool, it then being suitable for putting into a final assembly.

I claim:

1. An inertia switch comprising a body, opposed first 50 and second end walls, a side wall interconnecting said end walls to form said body having a cavity therein, a conductive slug within said cavity, means for urging said slug against said first end wall for sliding movement thereover and electrical contact means on said second end wall and said side wall, said slug having a protruding edge which engages said side wall when encountering centrifugal force on rotation of the body to form a pivot for the slug, thereby permitting the slug to hinge about the pivot when encountering longitudinal deceleration of 55 the body to bridge said electrical contact means and form a closed circuit between said electrical contact means on said end and side walls.

2. An inertia switch according to claim 1 wherein said urging means includes a spring in contact with said slug 60 near said second end wall.

3. An inertia switch according to claim 1 wherein said slug is of magnetic material and said urging means comprises a permanent magnet mounted to retain said slug near said first end wall.

70 4. An inertia switch comprising a body, first and second end walls, a conductive side wall interconnecting said end walls to form said body with a cavity therein, a

conductive slug within the body, means for urging said slug against said first end wall for sliding movement thereover, means insulating the slug from the side wall except on direct contact therewith, electric contact means provided on said second end wall and insulated from said side wall, said slug having a protruding edge which engages said side wall when encountering centrifugal force on rotation of the body to form a pivot for the slug, thereby permitting the slug to hinge about the pivot when encountering longitudinal deceleration of the body to contact the conductive portions of the second end wall and the side wall thereby to provide an electric current path between the side wall and the contact means on the second end wall.

5. An inertia switch comprising a body, first and second opposed end walls, the first end wall being electrically conductive and the second end wall being electrically non-conductive, an electrically conductive side wall interconnecting said end walls to form said body having a cavity therein, means insulating said side wall from said first end wall, an electrically conductive substantially cylindrically shaped slug within said cavity, means for urging said slug against said second end wall for sliding movement thereover, the circumference of said slug having an extending pivot edge which engages said side wall when responding to centrifugal force on rotation of the body to form a pivot point for the slug, whereby the slug hinges about the pivot on longitudinal deceleration of the body to contact the first end wall and thereby provide an electrical current path between the side wall and the first end wall.

6. An inertia switch comprising a cylindrical body formed by an electrically conductive disc, an insulating ring, an electrically conductive annulus, an insulating disc-shaped spacer and a disc-shaped permanent magnet, secured together in co-axial alignment in that order to provide a cavity within said body, an electrically conductive ferro-magnetic slug in said cavity held centrally on said spacer by the magnetic force exerted by said magnet, electrical leads secured to said electrically conductive disc and said annulus, said slug having a substantially cylindrical shape with a protruding circumferential edge for engaging the inside wall of said annulus when encountering centrifugal force on rotation

5 of said body about its longitudinal axis to form a pivot for the slug, so that the slug hinges about the pivot when encountering longitudinal deceleration of the body thereby contacting the electrically conductive disc to provide a current path between said conductive disc and said annulus.

10 7. An inertia switch comprising a cylindrical body formed by an electrically conductive disc, an insulating ring, a retainer spring, an electrically conductive annulus and a disc-shaped bottom plate secured together in co-axial alignment in that order to provide a cavity within said body, said spring being electrically insulated from said annulus, an electrically conductive slug in said cavity held centrally on said bottom plate by pressure of said spring, electrical leads secured to said electrically conductive disc and said annulus, said slug having a substantially cylindrical configuration with a protruding edge which engages the inside wall of said annulus responsive to centrifugal force on rotation of said body about its longitudinal axis to form a pivot for the slug, so that the slug hinges about the pivot when encountering longitudinal deceleration of the body to thereby contact the electrically conductive disc and provide a current path between said conductive disc and said annulus.

15 8. An inertia switch comprising a body with opposed first and second end walls, a side wall interconnecting said end walls to form a cavity within said body, a movable slug within said cavity slideable over said first end wall and having a protruding edge to engage the side wall when encountering centrifugal force on rotation of the body and to pivot thereon when encountering longitudinal deceleration of the body to urge said slug into contact with said second end wall, and electrical contact means on said second end wall operable to form a closed circuit when said slug is urged into contact therewith.
